DESIGN FOR A DISPLAY BOTTLE

Horace A. Fuld, New York, N. Y.

Application October 8, 1942, Serial No. 108,467

Term of patent 3½ years

To all whom it may concern:

Be it known that I, Horace A. Fuld, a citizen of the United States of America, residing in New York city, county of New York, and State of New York, have invented a new, original, and ornamental Design for a Display Bottle, of which the following is a specification, reference being had to the accompanying drawing, forming part thereof, wherein,

I claim:

The ornamental design for a display bottle, substantially as shown.

HORACE A. FULD.
